UNITED STATES PATENT OFFICE

131,909

DESIGN FOR AN AIRCRAFT CARRIER

Orlo A. Bartholomew, Northfield, N. J.

Application January 26, 1942, Serial No. 105,446

Term of patent 14 years

To all whom it may concern:

Be it known that I, Orlo A. Bartholomew, a citizen of the United States, residing in the city of Northfield, in the county of Atlantic and State of New Jersey, have invented a new, original, and ornamental Design for an Aircraft Carrier, of which the following is a specification, reference being had to the accompanying drawing, forming a part thereof, in which:

Fig. 1 is a top plan view of an aircraft carrier showing my new design;

Fig. 2 is a side elevational view thereof;
Fig. 3 is a bottom plan thereof;
Fig. 4 is an elevational view from the bow; and
Fig. 5 is an elevational view from the stern.

The present application is a continuation-in-part of my application for an aircraft carrier, Serial Number D-102,991, filed August 22, 1941.

I claim:

The ornamental design for an aircraft carrier, as shown and described.

ORLO A. BARTHOLOMEW.
